United States Patent Office

Des. 221,657
Patented Aug. 31, 1971

221,657

VAPORIZER BOWL OR THE LIKE

Lawrence Katzman, Edward Briggan, and Monte L. Levin,
New York, N.Y., assignors to Kaz Manufacturing Co.,
Inc., New York, N.Y.

Filed Mar. 30, 1970, Ser. No. 22,102

Term of patent 14 years

Int. Cl. D23—04

U.S. Cl. D23—148

FIG. 1

FIG. 2

FIG. 4

FIG. 3

FIG. 5

FIG. 1 is a front elevational view of a vaporizer bowl or the like embodying our new design;

FIG. 2 is a top perspective view thereof;

FIG. 3 is a bottom plan view thereof;

FIG. 4 is a rear elevational view thereof; and,

FIG. 5 is a side elevational view thereof, the other side being similar.

We claim:

The ornamental design for a vaporizer bowl or the like, as shown.
